UNITED STATES PATENT OFFICE.

CHARLES S. RUEF, OF DIXON, ILLINOIS, ASSIGNOR TO GRAND DETOUR PLOW COMPANY, OF DIXON, ILLINOIS, A CORPORATION OF ILLINOIS.

CULTIVATOR.

SPECIFICATION forming part of Letters Patent No. 764,257, dated July 5, 1904.

Application filed October 16, 1903. Serial No. 177,341. (No model.)

To all whom it may concern:

Be it known that I, CHARLES S. RUEF, residing at Dixon, Lee county, Illinois, have invented certain new and useful Improvements in Cultivators, of which the following is a specification.

My invention relates to cultivators of the sulky type; and the object thereof is to provide novel and efficient means for raising and lowering the different gangs of cultivators or shovels, as will be made apparent from the description hereinafter given.

In the drawings, Figure 1 is a perspective of my cultivator, showing one pair of gangs in lowered position and another pair in raised position; Fig. 2, a plan view of the left-hand half of the machine, but omitting the gangs; Fig. 3, a section taken centrally through shaft 13, quadrant or segment 20, and their bearings; Fig. 4, a detail of the lower end of the quadrant, the same being a sectional elevation on line 4-4 of Fig. 3; Fig. 5, a side elevation of the parts shown in Fig. 2, and Fig. 6 a detail view of the hand-operated levers.

The cultivator comprises in the present instance the wheels 1, having cranked axles 2 and a frame mounted thereon, to which the four beams 3, 4, 5, and 6 are pivoted in any well-known manner. These beams which may be of any desired number are connected together in two gangs by guide-arches 7 and 8, but arranged to have independent movement or adjustment by the means hereinafter described. As the manner of supporting or pivoting the beams forms no part of my present invention, but is well known in the art, the details thereof will not be explained. The cranked axles are connected to a frame, which consists of a rear transverse bar 9, resting upon such axles, and a front transverse bar 10, connected together by the two pairs of cross-bars 11 and 12. The raising and lowering mechanism about to be described is mounted upon this frame, particularly upon the cross-bars 11 and 12. As the two sets of raising and lowering mechanisms are similar in construction and operation the description of one will apply to both, and the one on the

left-hand side or half of the machine has been selected for the purposes of description.

A rock-shaft 13, which in the present instance is angular in section, is mounted in bearings 14 and 15, secured to the cross-bars 11 and 12, as shown clearly in Fig. 2. As illustrated in section in Fig. 3, the rock-shaft 13 has at its inner end a bearing sleeve or bushing 16, which fits within the bearing 15, and at the other end a similar sleeve. (Not shown.) The outer end of the rock-shaft—that is, the end adjacent the wheel—carries a crank-arm 17, which is connected to the left-hand beam 6 of the left-hand gang by means of a lifting-rod 18, with the result that whenever the arm 17 is rocked to elevate its outer end such beam will be raised. Upon the sleeve 16 on the inner end of the rock-shaft is loosely mounted the hub 19 of a quadrant 20, with which the two hand-levers 21 and 22 co-operate. The hand-lever 21, which in the form of machine illustrated is the shorter one of the two, is pivoted upon a pin 23 near its lower end to that portion of the quadrant forward of its pivotal axis. Through the medium of a link 24 the lower end of the lever 21 is pivotally and operatively connected to a crank-arm 25, which is secured upon the inner angular end of the rock-shaft 13. The lever 21 has a spring-pressed latch 26, co-operating with the teeth 27 of the quadrant and operated in the usual and well-known manner by the hand of the operator. It will thus be seen that the movements of the hand-lever 21 are communicated through the series of cranks and rock shaft to the outer beam 6, which will be raised or lowered independent of its companion beam, according to the direction of movement of the lever, but only when such lever 21 is disengaged from the quadrant. For instance, when the hand-lever 21 is in its lowered position, which is substantially a horizontal position, as indicated in the perspective, Fig. 1, the other lever 22 being in similar position, then the left-hand gang is in raised position, as shown; but when the hand-lever 21 is disengaged from the quadrant and raised the beam 6 will be lowered through

the mechanism described. The other hand-lever, 22, is also pivoted upon the pin 23 and is adapted to coöperate with the quadrant whose teeth are wide enough to permit the latch 28 of this lever to pass the latch 26 of the other lever without interference. The forward or lower end of the lever 22 extends beyond its pivotal point and is shaped to form a hook 29 to engage a chain 30, connected to a raising-rod 31, which is in turn connected to the beam 5. Obviously when the hand-lever 22 is in its lowered position, as shown, in respect to the left-hand set of raising and lowering mechanism now being particularly referred to, the beam 5, which it controls, is in raised position, as shown in the perspective, Fig. 1. The levers 21 and 22 are arranged to operate independently and also in unison through the medium of the quadrant, with the result that either one of the beams 5 or 6, for instance, may be raised or lowered independently of the other, or if either one of the levers is operated without disengagement from the quadrant both beams—that is, the entire gang—may be simultaneously raised or lowered, according to the direction of movement of such levers. The arch 7 coöperates with the beams 3 and 4 of the right-hand gang and the arch 8 with the beams 5 and 6 of the left-hand gang. To properly distance the two gangs without interfering with their independent raising and lowering, rods 32' 33' are provided, as seen in Fig. 1, which rods are pivotally connected at their outer ends to the arches, respectively, and held in adjustable relation to each other by any suitable means, as the clamp 24'. In order to supply the desired or necessary tension upon the movable or rocking quadrant, a curved link 32 is pivoted at its rearward end to the quadrant, while its forward end which is in advance of the rock-shaft 13 is connected to a chain 33, passing around a wheel 34. This chain is connected in turn to a spring 35, secured at one end to the transverse bar 9 of the machine-frame. The position of this quadrant, as shown by dotted lines in Fig. 5, is the extreme upward one, further movement being limited by the contact of the foot 36 on the cross-bar 12, Figs. 4 and 5. The full lines in Fig. 5 represent the lowered position of the quadrant, the left-hand quadrant, illustrated in the perspective, Fig. 1. When the quadrant is in its raised position, the pivotal point of the link 32, the axis of the rock-shaft, and the point of connection of the link and chain are in substantial alinement, and consequently the position of the quadrant, as shown, is maintained except as against positive force exerted by the levers or either of them thereupon.

As shown in the detail view, Fig. 6, the latch or dog of each hand-lever passes through the lower end of the lever and extends laterally to engage the teeth of the quadrant which, as hereinbefore stated, are sufficiently wide to

accommodate the latches of both levers without interfering one with the other, with the result that while both levers coöperate with the one quadrant for the purposes specified either one or the other of such levers may be swung or adjusted over the quadrant entirely independently. The levers pass or swing adjacent opposite sides or faces of the quadrant and are guided by the side strips or guides 36', as illustrated in Fig. 6.

I claim—

1. In a cultivator, the combination of a main frame, cultivator-beams supported thereby, a hand-lever for each beam, and means common to the levers of the beams whereby the manual operation of either one of the hand-levers will cause a simultaneous lowering or raising of the beams; substantially as described.

2. In a cultivator, the combination of a main frame, cultivator-beams supported thereby and arranged in gangs, and separate raising and lowering mechanisms for the gangs, each mechanism comprising a hand-lever for each beam, connections between the levers and the beams, and means common to the levers of the beams whereby the manual operation of either one of the hand-levers will cause a simultaneous lowering or raising of the beams; substantially as described.

3. In a cultivator, the combination of a main frame, a pair of cultivator-beams supported thereby, a hand-lever for each beam, and means common to both hand-levers for connecting or disconnecting them at the will of the operator; substantially as described.

4. In a cultivator, the combination of a main frame, cultivator-beams supported thereby, a hand-lever for each beam, and a quadrant mounted to move on said frame and coöperating with said levers to form a connecting medium between them; substantially as described.

5. In a cultivator, the combination of a main frame, cultivator-beams supported thereby, a hand-lever for each beam, and a quadrant pivoted on said frame and arranged to be engaged by said levers to form a connecting medium between them; substantially as described.

6. In a cultivator, the combination of a main frame, cultivator-beams supported thereby, a hand-lever for each beam, a quadrant pivotally mounted on said frame and coöperating with said levers to form a connecting medium between them, and means for limiting the upward forward movement of such quadrant; substantially as described.

7. In a cultivator, the combination of a main frame, cultivator-beams supported thereby, a hand-lever for each beam, a quadrant pivoted on said frame and arranged to be engaged by said levers to form a connecting medium, and means for imparting tension to the quadrant; substantially as described.

8. In a cultivator, the combination of a main

frame, cultivator-beams supported thereby, a hand-lever for each beam, a quadrant pivoted on said frame and arranged to be engaged by said levers to form a connecting medium, and a spring connected respectively with the quadrant and frame for imparting tension to the quadrant to assist the raising of the beams; substantially as described.

9. In a cultivator, the combination of a main frame, cultivator-beams supported thereby, a hand-lever for each beam, a quadrant pivoted on said frame and arranged to be engaged by said levers to form a connecting medium, a link pivoted to the quadrant, and a spring connected to the link and frame respectively for imparting tension to the quadrant; substantially as described.

10. In a cultivator, the combination of a main frame, cultivator-beams supported thereby, a hand-lever for each beam, a quadrant pivoted on said frame and arranged to be engaged by said levers, a link pivoted to the quadrant rearwardly of its pivotal axis and extending forwardly thereof, and a spring connected to the forward end of the link; substantially as described.

11. In a cultivator, the combination of a main frame, cultivator-beams supported thereby, a hand-lever for each beam, a quadrant pivoted on said frame and arranged to be engaged by said levers, a curved link pivoted to the quadrant rearwardly of its pivotal axis and extending around and forwardly of such axis, and a spring connected to the forward end of the link; substantially as described.

12. In a cultivator, the combination of a main frame, cultivator-beams supported thereby, a hand-lever for each beam, a quadrant pivoted on said frame and arranged to be engaged by said levers, a link pivoted to the quadrant, a pulley-wheel mounted in the frame, a spring attached at one end to the frame, and a chain passing over said wheel and forming a connection between the link and spring; substantially as described.

13. In a cultivator, the combination of a main frame, cultivator-beams supported thereby, a hand-lever for each beam, a quadrant pivoted on said frame and arranged to be engaged by said levers, a pulley-wheel mounted in the frame in advance of the quadrant, a curved link pivoted to the quadrant rearwardly of its pivotal axis and extending forwardly thereof, a spring attached at one end to the frame, and a chain passing over the wheel and connecting the spring and link; substantially as described.

14. In a cultivator, the combination of a main frame, cultivator-beams supported thereby and arranged in pairs or gangs, a hand-lever for each beam, and a quadrant coöperating with both levers of a gang and pivotally mounted on the frame, such quadrant having teeth adapted to be engaged by its said levers; substantially as described.

15. In a cultivator, the combination of a main frame, cultivator-beams supported thereby and arranged in pairs or gangs, a hand-lever connected to each beam, each lever having a spring-pressed latch or dog, and a quadrant pivotally mounted on the frame and having teeth sufficiently wide to coöperate with the latches of said levers without interference; substantially as described.

16. In a cultivator, the combination of a main frame, cultivator-beams supported thereby and arranged in pairs or gangs, and a raising and lowering mechanism for each gang, each mechanism comprising a rock-shaft mounted in the frame and having a crank-arm at one end, a connection between the crank-arm and one of the beams of a gang, a hand-lever operatively connected with such rock-shaft, a separate hand-lever operatively connected with the other of said beams, and a rocking quadrant with which both levers coöperate; substantially as described.

17. In a cultivator, the combination of a main frame, cultivator-beams supported thereby and arranged in pairs or gangs, and a raising and lowering mechanism for each gang, each mechanism comprising a rock-shaft mounted in the frame and having a crank-arm, a connection between such arm and one of the beams of a gang, a rocking quadrant mounted on such shaft, a hand-lever pivoted on the quadrant and operatively connected with the shaft, and a second hand-lever operatively connected with the other one of said beams, said levers both coöperating with said quadrant; substantially as described.

18. In a cultivator, the combination of a main frame, cultivator-beams supported thereby and arranged in pairs or gangs, and a raising and lowering mechanism for each gang, each mechanism comprising a rock-shaft mounted in the frame and having a crank-arm, a connection between such arm and one of the beams of a gang, a rocking quadrant mounted on such shaft, a hand-lever pivoted on the quadrant and operatively connected with the shaft, and a second hand-lever also pivoted on the quadrant and operatively connected with the other one of said beams, said levers both coöperating with said quadrant; substantially as described.

19. In a cultivator, the combination of a main frame, cultivator-beams supported thereby and arranged in pairs or gangs, and a raising and lowering mechanism for each gang, each mechanism comprising a rock-shaft mounted in the frame and having a crank-arm, a connection between such arm and one of the beams of a gang, a rocking quadrant mounted on such shaft, a hand-lever pivoted on the quadrant, a crank-arm on the other end of said shaft, a connection between said lever and the last-named crank-arm, and a second hand-lever operatively connected with the other one of said beams, said levers both

coöperating with said quadrant; substantially as described.

20. In a cultivator, the combination of a main frame, cultivator-beams supported thereby and arranged in pairs or gangs, and a raising and lowering mechanism for each gang, each mechanism comprising a rock-shaft mounted in the frame and having a crank-arm, a connection between such arm and one of the beams of a gang, a rocking quadrant mounted on such shaft, a hand-lever pivoted on the quadrant intermediate of the length of the lever, a crank-arm on the other end of said shaft, a link connection between said lever and last-named crank-arm, and a second hand-lever also pivoted on the quadrant and operatively connected with the other one of said beams, said levers both coöperating with said quadrant; substantially as described.
21. In a cultivator, the combination of a main frame, cultivator-beams supported thereby and arranged in pairs or gangs, and a raising and lowering mechanism for each gang, each mechanism comprising a rock-shaft mounted in the frame and having a crank-arm, a connection between such arm and one of the beams of a gang, a rocking quadrant mounted on such shaft, a hand-lever pivoted

on the quadrant and operatively connected with the shaft, a second hand-lever pivoted 30 intermediate of its length to the quadrant, and a connection between one end thereof and the other one of said beams, said levers both coöperating with the quadrant; substantially as described.

22. In a cultivator, the combination of a main frame, cultivator-beams supported thereby and arranged in pairs or gangs, and a raising and lowering mechanism for each gang, each mechanism comprising a rock-shaft 13 40 mounted in the frame, a crank-arm 17 at one end of the shaft, a rod 18 between said arm and one of the beams of a gang, a crank-arm 25 at the other end of the shaft, a quadrant 20 mounted loosely on the shaft, a hand-lever 45 21 pivoted on the lever, a link 24 connecting between the lever and crank-arm 25, a second hand-lever 22 also pivoted to the quadrant on the same axis as the first lever, and a connection between the second lever and 50 the other one of said beams; substantially as described.
